REFRIGERATION CONTROL VALVE

Keith E. Wilson, Los Angeles, Calif.

Application May 16, 1946, Serial No. 670,091

2 Claims. (Cl. 62—115)

1

The invention relates to a refrigeration control valve that enables the use of a receiver tank on a refrigeration system that uses a capillary tube, restrictor or orifice as the metering device; thereby allowing their use on all refrigeration systems, regardless of size, which has not been practical or safe without this control valve which prevents any dangerous pressure being developed in the system, affords automatic pump down in case of stoppage in the metering device, and pumps down for service and shipping purposes.

An object of the invention is to provide an improved control valve which is simple and compact in construction, highly efficient in operation and inexpensive to manufacture.

With the above and other objects and advantages in view the invention consists of the novel details of construction, arrangement and combination of parts more fully hereinafter described, claimed and illustrated in the accompanying drawing in which:

Figure 1 is a diagrammatic view of a refrigeration system with an embodiment of the invention installed therein;

Figure 2 is a vertical sectional view of the improved valve and

Figure 3 is a sectional view of a modified form of the invention.

Referring more in detail to the drawing, the reference numeral 10 designates the casing of the valve having the outlet opening 12 for connection to a capillary tube, orifice or restrictor and opening 14 for the connector 16 to connect the valve to the liquid receiver tank and the connector 16 is provided with the hexagon shoulder 18 for the manipulation thereof.

The casing 10 is provided with a threaded seat 20 to receive the shut off valve stem 22 of the shut off valve 23 which is provided with the seat 25 and communicates with the relief valve by passage 27, and a packing gland nut 24 and packing 26 provides a liquid tight joint between the stem and casing. The stem 22 is provided with the extension 29 which extends to a point adjacent the relief valve 28 which is urged against the seat 30 by a spring 32 which is retained in position by the connector 16.

A port 34 is drilled in the casing 10 and then closed by the plug 36 being soldered therein and the port communicates with the by-pass passage 38, which communicates by passage 42 with the check valve 44 and a spring 46 urges the valve 44 against the seat 48 which communicates with the relief valve 28 and a plug 50 is soldered in the

base 52 to retain the spring 46 in position and the casing is provided with the threaded opening 54 to receive the fitting 56 for connection to the outlet of the condenser.

5 The check valve and relief valve may be disc as shown or ball, conical or piston type using a material depending on type of refrigerant used.

In the modification shown in Figure 3, the pipe 58 from the condenser is connected to a two way backseating valve 60 which is connected to the receiving tank by a pipe 62 and a pressure relief valve 64, and check valve 66 are connected across the pipes 58 and 62. Thus three valves are used to control the refrigerant instead of one as shown in Figure 2. In this form of the invention the valve 60 is not constructed as shown in Figure 2, thus valve 64 will function as the valve 30 and valve 66 will function as the valve 44. Thus it will be seen that three separate and distinct units 20 must be used to perform the same operation as the valve shown in Figure 2.

In Figure 1 a typical hookup is shown employing the control valve wherein the capillary tube 68 is connected to the opening 12. The liquid receiving tank 70 is connected to the casing by the connector 16 and the condenser outlet 72 of the condenser 74 is connected to the fitting 56. The condenser 74 by connection to the compressor or pump 76 and the cooling coils 78 are interposed 30 between the compressor and capillary tube 68.

During the original operation of a system using this control valve, valve stem 22 is turned to unseat valve 23, which would allow the refrigerant in the receiving tank 70 to flow through check valve 44 and mix with refrigerant from the condenser 74 and flow through passage 38 out outlet 12 through capillary tube 68. During normal operation the refrigerant will pass through compressor 76 to condenser 74 to valve to capillary tube 68, which expands refrigerant into coils or evaporator 78 and then to suction side of compressor 76.

When the evaporator 78 reaches correct temperature the compressor 76 shuts off and the pressure in condenser 74 and in the valve drops to approximately the evaporator pressure, at this time any refrigerant in the receiving tank above the evaporator pressure will find its way out through connector 16 through check valve 44 as 50 before.

If at anytime a pressure is developed on the high side of the refrigeration system that is greater than the setting of the pressure relief valve 28 the refrigerant will pass through this valve out connector 16 into the receiver or storage

tank 70. The high pressure may be caused by oil slugging, dirt or freezing in the capillary tube 68, high room temperature causing high condenser pressure, power failures long enough to allow liquid refrigerant to settle in compressor crankcase, and by heavy loads placed on the evaporator coil such as storing a lot of warm products at one time or by having doors open during rush hours on warm days.

As soon as the cause of the high pressure is remedied the refrigerant starts leaving the receiver tank where it follows the course of flow previously mentioned.

The extension 29 on the stem 22 is for the purpose of opening relief valve for pump down purposes for shipment or repairs since it allows the pressure in the condenser and the receiver tank to remain equal and permits conventional method of service operations.

This valve provides complete safety and ease of service when a capillary, restrictor or orifice type of control is used on any size of refrigeration system.

In Figure 3 when the valve stem 80 is turned in the refrigerant travels from condenser to capillary tube connection 82 thereby by-passing the line to receiver tank which is closed. When the valve stem 80 is turned out the gas travels from condenser to receiver tank and the connection to capillary tube is closed tight.

It is believed the operation and construction of the valve will be apparent to those skilled in the art and it is to be understood that changes in the details of construction and arrangement of parts may be resorted to, provided they fall within the spirit of the invention and the scope of the appended claims.

Having thus described the invention, what is claimed as new and desired to be secured by Letters Patent is:

1. In an apparatus of the type described in-

cluding a compressor condenser, evaporator means and receiving tank for refrigerant connected in a closed circuit, the improvement comprising a valve assembly means including a supply inlet and the receiving tank connected to said inlet, said valve assembly means including a relief valve controlling the supply to said receiving tank and a check valve controlling the supply from said receiving tank to said relief valve, said valve assembly means being located in the circuit between the outlet of the condenser and the inlet to the evaporator means, a capillary tube between said valve and said evaporator, said valve adapted to compensate for pressure change in said circuit to permit normal flow of the refrigerant under normal pressure or bypass said refrigerant to said receiving tank upon rise of pressure through said relief valve and return said refrigerant to said circuit through said check valve upon reduction in pressure.

2. The improvement as in claim 1 wherein said valve assembly means is provided with a shut-off valve and said valve assembly means comprises a casing for housing the shut-off valve, the pressure relief valve and the check valve, and means is provided for connecting said casing to said evaporator means, condenser means and receiving tank.
